MULTISTAMP AUTOMATIC INKING
STENCIL DEVICE

Otto E. Borowetz, Plainfield, N. J.

Application November 14, 1935, Serial No. 49,685

5 Claims. (Cl. 101—125)

The main object of this invention is to provide a device for holding stencils for multigraphing machines and its purpose is to provide a machine equipped with an ink well, sealed so as to contain a vacuum pocket which permits a predetermined quantity of ink to penetrate the letters and characters on the stencil.

Another object of the invention is to provide an automatic multigraphing machine having a vacuum pocket adapted to be partly filled thru an aperture with ink, the vacuum retaining all but a minimum amount of ink within the ink well.

The above and other objects will become apparent in the description below in which characters of reference refer to like-named parts in the drawing.

Referring briefly to the drawing Figure 1, is a top plan view of the stenciling device with the cover removed therefrom to expose the mechanism therein for creating the vacuum pocket.

Figure 2 is a longitudinal, sectional, elevational view thru the stencil machine taken on line 2—2 of Figure 1.

Figure 3 is a cross sectional view taken on line 3—3 of Figure 1.

Referring in detail to the drawing the numerals 10 and 11, indicate the end walls of a casing which is composed of several members. A substantially semi-circular plate 12, forms the remainder of the casing and is provided with perforations 13, against the inside of which a stencil sheet is secured. The plate 12, is secured to and has its ends embedded within a rectangular frame member 14. The end walls 10 and 11, have right angle lips 15, thereon beneath which the edges of a cover member not shown on the drawing is slidably received. Along the interior edges of the frame 14, a plurality of inwardly extending studs 40 16, are provided, these stud members are adapted to receive thereon and support clutch bars 17, 18, 19, and 20. The bars have a semi-circular face 21, and are adapted to have situated between them and the frame member 14, and sides 10 45 and 11, a semi-circularly formed flexible rubber pouch 22. Extending from the frame sides 14, of the device on each side of the latter and inwardly are pairs of supporting rods 23 and 24. These rods extend outwardly in a horizontal 50 plane and are provided with hollowed out cradles 25, in which carrier handles 26 and 27, are supported. The handles extend longitudinally in the device and are secured to the pouch 22, by screws 28. Each of the studs 16, are provided 55 with a wing nut by means of which the edges of

the rubber pouch 22, are compressed to form a leak proof fit between the outer device and the rubber pouch so as to provide a vacuum pocket 29, beneath the pouch and between the pouch member and the perforated plate 12. In order to partly fill the well 29, with ink of the multigraphing type an opening is provided in the pouch into which a stopper 30, is threaded.

This device may be presented in modified form and eliminate the pairs of rods 23 and 24. Instead of securing rods to the frame bars 19 and 20, such as those indicated by the numerals 23 and 24, the studs 16, may be extended at convenient positions so as to form a support for the handles 26 and 27. 15

The device in use is adapted to serve as a machine upon which stencils are mounted for purposes of multigraphing sets of characters by rolling a stencil surface over a sheet of paper or the like for an impression. The stencil is secured to the outer surface of the plate 12, in any desired manner. Ink is filled into the well 29, after removing the threaded stopper 30, care being taken that at this operation the handles 26 and 27, are not supported by the rods 23 and 24, when the ink has been filled and the stopper caps the opening the handles are lifted to supporting position upon the rods 23 and 24, and the rubber pouch 22, assumes the position shown in Figure 2. This operation produces a partial vacuum in the well 29, and prevents an excessive flow of ink from the perforations 13 in the plate 12, of the surface of the stencil. A vacuum is absolutely necessary in the well 29, or otherwise excessive ink would flow due to capillary attraction. 35

It is to be noted that certain changes in form and construction may be made without departing from the spirit and scope of the invention.

I claim:

1. In a device of the class described a casing having a perforated semi-circular bottom adapted to have a stencil mounted thereon, a rubber pouch secured in said casing, a frame comprising bars adapted to compress the edges of the said pouch, means for securing said bars to said casing and means for retaining said pouch in lifted position in said casing. 40

2. In a device of the class described a casing having a perforated semi-circular bottom adapted to have a stencil mounted thereon, a rubber pouch secured in said casing, a frame comprising bars adapted to compress the edges of the said pouch, threaded studs projecting from said casing internally, said studs, having said bars mounted 50

thereon and means for supporting said pouch on said bars.

3. In a device of the class described a casing having a perforated semi-circular bottom adapted to have a stencil mounted thereon, a rubber pouch secured in said casing, a frame comprising bars adapted to compress the edges of the said pouch threaded studs projecting from said casing internally, said studs having said bars mounted thereon, rods extending sidewise from said bars, said studs having wing nuts thereon, to secure said bars to said casing, and means on said pouch for suspending the latter from said rods.

4. In a device of the class described a casing having a perforated semi-circular bottom adapted to have a stencil mounted thereon, a rubber pouch secured in said casing, a frame comprising bars adapted to compress the edges of the said pouch threaded studs projecting from said casing internally, said studs having said bars mounted thereon, rods extending sidewise from said bars,

said studs having wing nuts thereon, to secure said bars to said casing, handles on said pouch adapted to be supported by said rods to form a vacuum well between said pouch and said bottom of said device.

5. In a device of the class described a casing having a perforated semi-circular bottom adapted to have a stencil mounted thereon, a rubber pouch secured in said casing, a frame comprising bars adapted to compress the edges of the said pouch threaded studs projecting from said casing internally, said studs having said bars mounted thereon, rods extending sidewise from said bars, said studs having wing nuts thereon, to secure said bars to said casing handles on said pouch adapted to be supported by said rods to form a vacuum well between said pouch and said bottom of said device, said rods having saddles thereon adapted to receive said handles for lifting said pouch to lifted position.

OTTO E. BOROWETZ.
